UNITED STATES PATENT OFFICE.

HERBERT H. WALTERS, OF SYRACUSE, NEW YORK.

FIREPLACE

Application filed March 14, 1927. Serial No. 175,246.

This invention relates to a hollow fireplace as a unitary article of manufacture adapted to be installed in a recess in a chimney to form an interior air chamber and an exterior combustion chamber and provided with one or more smoke pipes or conduits extending therethrough to permit the passage of the products of combustion from the combustion chamber to the smoke flue without contact with the air in the air chamber and also provided with a cold air inlet and a warm air outlet communicating with the air chamber whereby the cold air entering said chamber will be heated and delivered through the outlet to the interior of the room to be heated.

The main object is to provide a fireplace of this character capable of being easily and quickly installed and substantially concealed within the chimney for utilizing the heat produced by the combustion of the fuel for maintaining a continuous circulation of warm air from the exterior through the shell and to the interior of the room to be heated and at the same time to radiate the heat from the smoke pipes passing therethrough to the air in the air chamber for additionally heating the air in transit from the cold air inlet to the warm air outlet.

Another object is to provide means for opening and closing communication between the cold air inlet and the warm air outlet so that when no combustion is taking place in the combustion chamber the communication between the inlet and outlet may be cut to prevent the entrance of cold air into the room.

Another object is to provide means for opening and closing communication between the smoke flue of the smoke and combustion chamber so that when the fire is out such communication may be closed to prevent the entrance of cold air from the chimney into the combustion chamber and thence into the room.

Other objects and uses will be brought out in the following description.

45 In the drawings:

Figure 1 is a front elevation of a portion of a chimney and my improved fireplace installed therein.

Figure 2 is a vertical sectional view taken in the plane of line 2—2, Figure 1.

Figure 3 is a horizontal sectional view taken in the plane of line 3—3, Figure 2.

Figure 4 is an enlarged top plan of the upper portion of the detached fireplace showing

a part of the top wall broken away and underlying flues of the smoke conduits in section.

55 Figure 5 is a sectional view taken in the plane of line 5—5, Figure 4.

Figure 6 is a transverse vertical sectional view taken in the plane of line 6—6, Figure 5.

In order that this invention may be clearly understood I have shown a portion of a chimney —1— as enlarged at —2— and provided with a recess —3— in the enlarged portion 60 for receiving the hollow fireplace presently described, said chimney being provided with a suitable smoke flue —4— communicating with the recess through a downwardly flaring enlargement —5—, the lower wall of 70 which is preferably made of concrete with a concave upper surface —6— at about the level of the top of the fireplace for deflecting any down draft current of air containing more or less smoke content upwardly thereby reducing the liability of passage of the down draft currents into the open front side of the recess.

75 The chimney proper may be made wholly or in part of brick or other suitable refractory material and is provided in its lower front side with an opening —7— communicating with the recess —3— and extending from the floor tiling as —8— to a level a short distance below the top portion of the hollow fireplace.

80 The fireplace forming the subject matter of this invention consists in this instance, of a hollow sheet metal shell comprising a hollow upright back portion —9—, opposite upright hollow portions —10— projecting forwardly from opposite upright edges of the back portion and a substantially horizontal hollow top portion —11— extending forwardly from the upper end of the back portion —9— and between the upper ends of the side portions —10— thereby forming a combustion chamber —12— and an air chamber —13— which is continuous from top to bottom of the back portion —9—, side portions —10— and top portion —11—.

85 The lower end of the hollow back portion —9— is provided with a horizontal rearward extension —14— having a cold air inlet passage —15— thereby and a grill plate —16— across the rear end of the passage —15—.

90 The top portion —11— extends forwardly beyond the front faces of the side portions —10— and is provided with a grill plate

—17— across the front face thereof to allow the warm air to pass into the room in which the fireplace is located as it is heated in transit from the cold air inlet —15— to the 5 warm air outlet as —18— in the horizontal top portion —11—.

The brick work of the chimney preferably extends across the back and opposite sides of the sheet metal fireplace and across the front 10 faces of the sides —10— and also surrounds the top, bottom and sides of the forward end of the upper horizontal portion —11— and the horizontal rearward extension —14— as shown more clearly in Figure 2 so that the 15 only portions of the fireplace which are exposed are the grill plates —16— and —17— and the back and side portions —9— and —10— just at the rear of the front wall of the chimney in which the fuel opening —7— 20 is formed.

The top and bottom walls of the upper horizontal portion —11— of the fireplace are provided with vertically aligned apertures in which are tightly fitted the lower and upper 25 ends of suitable smoke conduits —19— which extend across the adjacent portion of the air chamber for conducting the products of combustion from the combustion chamber —12— through the top portion —11— and into the 30 smoke flue —5— of the chimney, the joints between the smoke conduits and lower and upper walls of the top portion —11— being gas-tight to prevent the passage of any part of the products of combustion from the combustion chamber into the air chamber.

A deflector plate —20— is secured to the top wall of the horizontal portion —11— to extend upwardly and rearwardly over the upper ends of the smoke conduits —19— and 40 thereby to assist in deflecting the products of combustion escaping through said smoke conduits into the smoke flue of the chimney, the rear edge of the deflector plate terminating approximately in the vertical plane of the 45 axes of said smoke conduits.

A damper —21— is hinged at —22— to the top wall of the horizontal portion —11— to swing to and from a position across the upper 50 ends of the smoke conduits —19— and into and out of engagement with the upper rear edge of the deflector plate —20— for opening and closing communication between said conduits and the main smoke flue of the chimney and thereby to not only regulate the draft to 55 the combustion chamber but also to prevent back draft from the main smoke flue —4— through the smoke conduits —19— and into the combustion chamber and thence out into the room through the fuel opening —7—.

60 Any suitable means may be provided for operating the damper —21—, said means consisting, in this instance, of a crank arm —23— secured to the damper —21— near one end thereof and pivotally connected to the rear 65 end of a forwardly and rearwardly movable

operating rod —24— which extends through an aperture —25— in the front grill plate —17— and is provided at its front end with a handle —26— by which it may be manipulated.

70 In the use of this hollow sheet metal fireplace it is desirable to provide means for preventing the passage of cold air from the inlet —15— through the air chamber and thence through the outlet —18— particularly 75 when there is no fire in the combustion chamber and for this purpose is provided a pair of dampers —27— pivoted at —28— to the inner faces of the lower and upper walls of the horizontal portion —11— so as to extend 80 toward each other between the smoke conduits —19— and front grill plate —17— so that when closed they extend substantially 85 the entire distance between the lower and upper walls of said horizontal portion —11— 90 and from end to end thereof.

These dampers —27— are connected by links —29— to the rod —24— so that when the rod is pulled forwardly to open the damper —21— the dampers —27— will also 95 be opened and reversely the closing of the damper —21— by the rod —24— will also 100 close the dampers —27— thereby preventing back draft from the main flue —4— of the chimney into the combustion chamber and 105 also preventing the passage of cold air from the outside of the fireplace into the room in which the fireplace is located through the air chamber of said fireplace.

Operation.

110 The fuel to be burned is placed through the opening —7— into the combustion chamber —12— in any suitable manner and when ignited the products of combustion will impinge 105 against the inner walls of the back portion —9— and side portions —10— and also against the lower side of the upper horizontal portion —11— and will then pass out through the smoke conduits —19— into the main 110 smoke flue of the chimney when the damper —21— is opened.

115 The air in the air chamber as —13— of the hollow sheet metal fireplace will then be heated by the products of combustion and will cause a circulation of the cold air from the inlet —15— upwardly through the chamber —9— and thence outwardly through the grill plate —17— into the room to be heated, it being understood that when combustion is 120 taking place in the combustion chamber, the dampers —21— and —27— will be open.

125 The inner walls of the sheet metal fireplace are co-extensive with the area of the combustion chamber and thereby all of the heat developed in said combustion chamber will be transferred through the inner walls of the sheet metal shell to the air in the chamber —9— throughout the area of said walls thereby causing an upward circulation of the 130

cold air in the bottom of the chamber —9— to pass upwardly and outwardly through the grill —17—.

What I claim is:—

- 5 1. The combination with a chimney having a recess for receiving a fireplace and provided with a smoke flue leading from the top of the recess, of an open fireplace comprising a hollow metal shell having upright back and side portions and a substantially horizontal top portion, said shell having a cold air inlet near the bottom of the back portion and a warm air outlet in the front end of the horizontal top portion, smoke flues extending vertically through the horizontal top portion some distance from the front and rear ends thereof, a deflector plate secured to the top wall of the horizontal portion of the shell in front of the smoke flues and extending upwardly and rearwardly over the central portions of the smoke flues, a damper hinged to said top wall at the rear of the smoke flues to swing forwardly and rearwardly into and out of engagement with the upper edge of the deflector plate, a damper composed of sections hinged to the lower and upper walls of the horizontal top portion to swing forwardly and rearwardly, and means for operating said dampers.
- 10 2. The combination with a chimney having a recess for receiving a fireplace and provided with a smoke flue leading from the top of the recess, of an open fireplace comprising a hollow metal shell having upright back and side portions and a substantially horizontal top portion, said shell having a cold air inlet near the bottom of the back portion and a warm air outlet in the front end of the horizontal top portion, smoke flues extending vertically through the horizontal top portion some distance from the front and rear ends thereof, a deflector plate secured to the top wall of the horizontal portion of the shell in front of the smoke flues and extending upwardly and rearwardly over the central portions of the smoke flues, a damper hinged to said top wall at the rear of the smoke flues to swing forwardly and rearwardly into and out of engagement with the upper edge of the deflector plate, a damper composed of sections hinged to the lower and upper walls of the horizontal top portion to swing forwardly and rearwardly, and means for operating said dampers.
- 15 3. The combination with a chimney having a recess for receiving a fireplace and provided with a smoke flue leading from the top of the recess, of an open fireplace comprising a hollow metal shell having upright back and side portions and a substantially horizontal top portion, said shell having a cold air inlet near the bottom of the back portion and a warm air outlet in the front end of the horizontal top portion, smoke flues extending vertically through the horizontal top portion some distance from the front and rear ends thereof, a deflector plate secured to the top wall of the horizontal portion of the shell in front of the smoke flues and extending upwardly and rearwardly over the central portions of the smoke flues, a damper hinged to said top wall at the rear of the smoke flues to swing forwardly and rearwardly into and out of engagement with the upper edge of the deflector plate, a damper composed of sections hinged to the lower and upper walls of the horizontal top portion to swing forwardly and rearwardly, and means for operating said dampers.
- 20 4. The combination with a chimney having a recess for receiving a fireplace and provided with a smoke flue leading from the top of the recess, of an open fireplace comprising a hollow metal shell having upright back and side portions and a substantially horizontal top portion, said shell having a cold air inlet near the bottom of the back portion and a warm air outlet in the front end of the horizontal top portion, smoke flues extending vertically through the horizontal top portion some distance from the front and rear ends thereof, a deflector plate secured to the top wall of the horizontal portion of the shell in front of the smoke flues and extending upwardly and rearwardly over the central portions of the smoke flues, a damper hinged to said top wall at the rear of the smoke flues to swing forwardly and rearwardly into and out of engagement with the upper edge of the deflector plate, a damper composed of sections hinged to the lower and upper walls of the horizontal top portion to swing forwardly and rearwardly, and means for operating said dampers.
- 25 5. The combination with a chimney having a recess for receiving a fireplace and provided with a smoke flue leading from the top of the recess, of an open fireplace comprising a hollow metal shell having upright back and side portions and a substantially horizontal top portion, said shell having a cold air inlet near the bottom of the back portion and a warm air outlet in the front end of the horizontal top portion, smoke flues extending vertically through the horizontal top portion some distance from the front and rear ends thereof, a deflector plate secured to the top wall of the horizontal portion of the shell in front of the smoke flues and extending upwardly and rearwardly over the central portions of the smoke flues, a damper hinged to said top wall at the rear of the smoke flues to swing forwardly and rearwardly into and out of engagement with the upper edge of the deflector plate, a damper composed of sections hinged to the lower and upper walls of the horizontal top portion to swing forwardly and rearwardly, and means for operating said dampers.

In witness whereof I have hereunto set my hand, this 10 day of February, 1927.

HERBERT H. WALTERS.
